2 SHEET S-SHEET 2.

UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC-SWITCH DEVICE.

1,086,539.

Specification of Letters Patent. Patented Feb. 10, 1914.

Application filed May 19, 1911. Serial No. 622,153.

To all whom it may concern:

Be it known that I, CHARLES J. KLEIN, a citizen of the United States, residing at Milwaukee, in the county of Milwaukee and State of Wisconsin, have invented new and useful Improvements in Electric-Switch Devices, of which the following is a full, clear, concise, and exact description, reference being had to the accompanying drawing, forming a part of this specification.

My invention relates to electric switch devices.

While my invention may be used in various relations, in one of its adaptations it more especially relates to electric switch devices of the type known as candelabra switches, that is, to switches used in connection with candelabra lights wherein the light is inclosed in a casing which gives it the appearance of a candle. In this application, I shall for purposes of illustration describe my invention as applied to a switch of this type.

One of the objects of my invention is to provide an improved electric switch of extremely simple, efficient and inexpensive construction.

A further object of my invention is to provide an improved switch device which may be used with any candle fixture of standard form without any material alteration of the fixture.

Other objects and advantages of my invention will be hereinafter set forth.

In the accompanying drawings I have for purposes of illustration shown one form which a switch device constructed in accordance with my invention may assume in practice. My invention itself, however, is not limited to this specific form chosen to illustrate the same, but is capable of being widely modified without departing from its principle. All of these various forms fall within the purview of my improvement.

In the views of the drawings Figure 1 shows a side elevation of a switch mounted in position in the candle fixture, the fixture being shown in dotted lines. Fig. 2 shows a sectional view of the switch. Fig. 3 shows a central sectional view of the switch base when assembled. Fig. 4 shows a bottom plan view of the switch base. Fig. 5 shows a perspective view of an insulating spacing

strip for the switch terminals in position on the upper surface of the base. Fig. 6 shows a perspective view of the supporting spider for the switch base. Fig. 7 shows a perspective view of an insulating spacing washer for positioning the parts and insulating the same. Fig. 8 shows a side elevation of the switch spring in position on the switch cam. Fig. 9 shows a half section of the switch contactor. Fig. 10 shows a cross section on line 10—10 of Fig. 1.

In these figures I have shown a switch mechanism of the push button type housed between the members 1 and 2 of a suitable base composed preferably of insulating material, which is clamped together by the terminal members 2 of the switch. The base 70 when assembled is of substantially cylindrical cross section, and is arranged to be mounted in a candle cup 4 of the standard construction so that the ends of the push buttons 5 extend through holes 6 bored in the opposite sides of the cup. In order to support the base within the cap, a spider 7 is provided which grips the lower part of the lower base member 2, and is provided with a central threaded sleeve 8 adapted to be screwed upon the end of a standard fixture nipple 9. A candle 10 is seated upon the upper surface of the base member 1 which is stepped as at 11 to accommodate candles of different sizes, and an adjustable threaded spindle 12 is centrally located in a threaded sleeve 13 carried in the upper base member. This spindle 12 extends vertically upward within the candle 10 and is provided at its upper end with a threaded sleeve or socket 90 receiving member 14 adapted to receive a candelabra socket 15 which in turn supports a suitable lamp in the open end of the candle.

The switch mechanism is preferably of the type described in my Patent No. 985,421, patented February 28, 1911. This mechanism includes a reciprocable cam 16 of the conformation of a double frustum positioned base to base, which is preferably constructed of one piece of cast metal and provided with flanges 17 at its reduced ends. This cam member 16 is provided with a central bore threaded to receive a longitudinally extending threaded shaft 18 which extends through the cam member and is arranged to carry indicating push buttons 5 on its oppo-

site ends. One of these buttons may be black and the other white so that the condition of the switch is indicated by which button is visible. These push buttons 5 are provided with threaded bores 19 adapted to receive the ends of the threaded shaft 18 extending beyond the ends of the cam 16 and are arranged to be removable so that the switch mechanism may be placed in position in a candle cup and the push buttons then screwed in through holes bored in the cup without any necessity for destroying the appearance of the cup by slotting the same. If desired the threaded shaft 18 may be fixed within one of the push buttons so that it will rotate and be removable with one of the same. When in assembled relation the outer ends of the push buttons extend through the holes 6 in the candle cup 20 so that either the black or white button is visible, while their inner ends abut against the outer vertical surfaces of the flanges 17 of the cam member. This cam member is mounted in a recess or chamber 19' in the 25 upper surface of the lower base member 2 and is adapted to be reciprocated across the same, the push buttons 5 extending through the oppositely disposed alined grooves 6' at the sides of the chamber 19', which are 30 slightly less deep than the chamber 19', and are provided with rounded bottoms to receive the push buttons. The flanges 17 on the cam member are adapted to engage the walls of the chamber 19' so that these walls 35 establish the limits of travel of the cam member and the cam member in its movement across the base between the limits of travel is arranged to expand a garter spring 21 which encircles the cam and is carried 40 within a movable contactor 22 hereinafter described. When the garter spring 21 is expanded and moves over the crest of the cam 16, the contactor 22 is thrown to one of the limits of its travel in a recess 23 of 45 substantially rectangular cross section in the lower base member 2. Due to the provision of the spring 21 and the action of the cam 16 the contactor 22 is thrown with a quick snap action to make or break contact with 50 the switch terminals 3 located at one end of the chamber 23 and against the wall of the same. The upper base member 1 is provided with a chamber 24 of substantially rectangular cross section in its lower surface 55 which is adapted to fit over the chamber 23 in the lower base member when the parts are assembled, but which is not quite as wide or deep as the chamber 23. This chamber 24 with the chamber 23 provides a 60 suitable chamber for the switch contactor and this latter is adapted to be reciprocated by the cam member from one side of this chamber to the other. One of the limits of the switch contactor is established by the walls of the chambers 23 and 24. In the

construction shown in Fig. 2 for instance the left hand limit of travel is established by these walls. The other limit of travel of the contactor is established by the contact terminals 3 at the opposite side of the chambers. These terminals 3 extend vertically upward through suitable parallel recesses in the two base members 1 and 2 which extend through the chamber 23 and communicate with the chamber 24, and serve the double function of providing the terminals for the switch mechanism and at the same time providing means for clamping the parts of the base together. In a preferred form these terminal members have long shanks of substantially rectangular cross section and are provided with enlarged heads 25 at their upper ends which carry suitable binding screws 26, and are provided with laterally disposed ears 27 on the opposite sides of the binding screws. The upper ends of these terminals 3 are spaced apart by an insulating spacing strip 28 which is preferably seated in a recess 29 in the upper surface of the base member 1 and formed of stamped insulating material and provided with rectangular shaped perforations or slots 30 which accurately fit the terminals. Since this strip 28 may be very accurately stamped, it serves to position the terminal members very accurately in the bases. The lower ends of the terminals 3 are preferably screw threaded as at 31 and extend into recesses 32 in the bottom surface of the lower base 2. The recesses 32 communicate with each other through a recess 33 of reduced cross section, and an insulating spacing strip 34 similar to the strip 28 is preferably placed in position over the lower ends of the terminals to position the latter in the same manner as described above. Taps 35 may be placed upon the threaded ends of the terminals 3 and these ends and the taps may be sealed in the recesses by a suitable composition as at 36.

In a preferred form a spider 7 having a screw threaded bore 8 and two or more upwardly extending prongs 37 is adapted to be slipped over the end of the lower base member so that the threaded portion 8 is concentric with the base member. In a preferred form one of these prongs is slightly shorter than the others. In order to provide means for presenting the relative rotation of the lower base and the spider, and to hold the parts securely together the prongs 37 of the spider are preferably received in vertically extending recesses or slots 38 provided in the periphery of the lower base member. By the use of a short prong and a correspondingly shaped recess the parts may be more readily assembled since the correct position of the same may be determined at a glance. The prongs 37 preferably extend obliquely upward from

the base of the spider 7 and are then bent vertically upward as illustrated in Fig. 6, and in a preferred form the slots 38 in the base member are so formed as to permit these prongs to lie flat against the bottoms of the slots. The spider 7 is adapted to be screwed over the end of a standard fixture nipple 9 which is received within the threaded portion 8 of the spider. The conductors for the switch are brought in through this nipple and are brought upward through the spider to the terminals of the switch.

In order to provide ample room for the conductors I preferably slightly dish the lower surface of the lower base member 2 as at 39 and in order to prevent the rubbing of the conductors and possible short circuits within the switch, I preferably place an insulating washer 40, provided with suitable notches 41 adapted to receive the conductors, between the upper surface of the threaded sleeve 8 and the lower surface of the base 2. After the conductors have been brought in through the nipple and passed through the spider 7, the ends of the same are brought outward through the slightly rounded ends of vertically disposed grooves 42 on opposite sides of the base members 1 and 2 and between the slots 38. These grooves 42 are provided with rounded ends and bottoms so that the conductors may fit snugly within the same without wearing their insulation, and extend as illustrated in Fig. 3 upward along the sides of the bases and through the stepped portion 11 of the upper base to points adjacent the binding screws 26 of the terminal members 3. One of the conductors is adapted to be connected to one of the binding screws 26, as for instance the right hand binding screw as illustrated in Fig. 1. The other of the conductors is adapted to be connected to a binding screw 43 carried on the socket 15 and a short length of conductor is connected between the other binding post 44 of the socket to the other binding screw 25 on the top of the base. These conductors are thus passed up around the vertical spindle 12 and are so arranged that they may be inclosed by the candle 10 when the candle is placed in position on the upper base 1 and lie snugly within the stepped portion 11 of the base without interfering with the seating of the candle.

In order to prevent the rattling of the candle when the fixture is jarred, and also maintain the conductors in their proper position, I provide an insulating washer 45 of triangular shape. This washer 45 is preferably placed upon the spindle 12 at a point between the threaded ends and is of such a diameter as to fit within the candle 10 when the latter is slipped over the spindle 12. It is to be noted that this spindle 12

is screw threaded at both its ends so that it may be adjusted to suit candles of different heights. The threaded sleeve 13 in which it is supported in the upper base member 1 may consist of a single piece of metal riveted in the base member, or if desired may be formed of two threaded parts adapted to be placed in position from the top and bottom of the base member and screwed into their proper relation.

In Fig. 9 I have illustrated an improved form of switch contactor adapted to make a good contact with no injurious shock to the switch mechanism. In order to facilitate the illustration only one half of this contactor has been shown. It is to be understood, however, that the other half is identical with the portion illustrated. This contactor is preferably formed of a single strip of thin resilient sheet metal which is stamped with perforations 46 and bent into the form shown in Fig. 9 so that the perforations 46 are directly opposite each other and the body portions 22 of the contactor is of substantially U shape. Extensions 47 are preferably provided on each side of one of the U arms, and these extensions 47 are bent over at right angles to the arm so that they lie against the outer edges of the other U arm and extend slightly beyond the outer surface of the same. These arms 47 form the contact surfaces for the switch and are adapted to engage the sides of the contact terminals 3 with a wiping contact. In order to provide a better contact with the contact members 3, the vertical edge of the extensions 47 are preferably slightly turned outward as at 49.

In order to facilitate the bending of the parts of the contactor into the shape shown in Fig. 9, and to increase their resiliency, I may slightly notch the edges of the strip from which the contactor is made at the points where the extensions 47 are bent as indicated at 50. Further, in order to permit the garter spring 21 to expand freely within the contactor without rubbing against the walls of the same when the cam member is reciprocated, I preferably punch out portions of the extensions 47 as indicated at 51. When the parts are in assembled relation, the contactor 22 is carried upon the cam member 16 as shown in Fig. 2, the cam member passing through the perforations 46 in the contactor 22 and the garter spring 21 being housed within the contactor as shown in that figure and gripping the surface of the cam 16.

When the switch mechanism is in the position shown in Fig. 2, the circuit of the switch is closed, since the terminals 3 are bridged by the contactor 22. When however, the left hand push button 5 is pushed in, the cam 16 is moved toward the right through the contactor 22 to expand the garter spring 21.

At the moment the garter spring passes over the crest of the cam 16 it immediately contracts, and as it does so it moves rapidly down the inclined face at the left hand side 5 of the crest throwing the contactor 22 to the open circuit position with a quick snap action, the contactor 22 reaching the limit of its travel against the walls of the chambers 23 and 24 at substantially the same time that 10 the right hand flange 17 on the cam 16 abuts against the right hand wall of the chamber 19'. When the push button is pushed to close the switch, the contactor 22 is moved with the same quick snap action and the 15 out-turned vertical edges 49 of the contactor 22 engage the sides of the terminal members 3 with a wiping action tending to keep the contacts clean and pass in between the terminal members 3 and the sides of the chambers 23 and 24 in the space marked 52 on 20 Fig. 3. The forward limit of travel of the contactor 22, established by the engagement of the body portion of the contactor with the front edge of the terminals 3, and the 25 forward limit of the travel of the cams 13 against the wall of the chamber 19' is reached at substantially the same time so that the shock is absorbed and the parts are put under no strain.

30 By my improved construction I have provided an improved switch in which the number of necessary parts has been reduced by the use of the terminal members as the means for holding the base members in assembled 35 relation. Further, by the use of the insulating spacing strips for the terminal members I have been able to very accurately position these terminal members in the switch. By the provision of the spider support which 40 is adapted to be threaded on to the end of a standard fixture nipple, I have been able to provide a secure and stable support for the switch mechanism and one which will permit of screwing the switch support and 45 the candle cup to the fixture at the same time so that the switch may be inserted without twisting the conductors.

By the use of my improved push button switch mechanism I have provided a device 50 which is peculiarly well adapted to use with lamps having fragile filaments since the switch mechanism operates so smoothly that the filaments are subjected to no injurious shocks. Further, by the provision of the 55 detachable push buttons for the switch I have provided a switch mechanism which may be readily placed in position in a standard candle cup with the necessity for boring but two small holes on opposite sides of the 60 cup, and have thus been able to do away with the necessity for slotting the cup and causing the same to present an unsightly appearance. Further, by the use of the indicating push buttons the condition of the 65 switch may be determined at a glance.

By the provision of the improved socket support and the insulating washer I am able to prevent the rattling of the candle and to provide an improved adjustable support for the socket adapted to use with candles of different heights. By the provision of the stepped top of the upper base member I have also provided a device which is adapted to use with candles of various diameters. By the provision of the grooves in the sides 70 of the bases I have provided a device in which the conductors may fit very snugly in the bases and be protected by the same so that the switch is very compact and serviceable. Numerous other advantages of my 75 improved construction will readily appear to those skilled in the art.

While I have in this application described one specific form which my invention may assume in practice, I have only described this 80 form as a means of illustrating the principle of my invention and do not wish to be limited to this specific form since my invention itself is capable of assuming various other forms and of being widely modified and 85 adapted to various other uses.

What I claim as new and desire to secure by Letters Patent is:—

1. In an electric fixture, a candle cup 90 having holes in its opposite sides and a snap switch mechanism carried by said cup and having removable push buttons extending through said holes.

2. In an electric switch device, a base, a switch mechanism inclosed therein, a spindle carried by said base and insulated therefrom and arranged to support a socket and removable means for attaching said base to a support.

3. In an electric switch device, a two part 105 casing, a switch mechanism inclosed therein, terminal contacts extending therethrough and arranged to hold the parts of the casing together, binding posts carried on the upper ends of said terminal contacts, and means 110 arranged to support a socket.

4. In combination, a base having a plurality of parts, a push button snap switch mechanism inclosed therein, terminal members for said switch mechanism arranged to 115 hold the parts of said base together, and a socket supporting spindle carried by said base and insulated therefrom.

5. In an electric switch device, the combination of a base having a plurality of 120 parts, a snap switch mechanism inclosed therein, terminal members for said switch arranged to hold the parts of said base together, adjustable means for supporting a lamp socket above said base, and means carried by said base for attaching the same to a support.

6. In an electric switch device, a base, a snap switch mechanism inclosed therein and means for supporting said base including a 125

- spider having a central sleeve and a plurality of prongs arranged to grip said base.
7. In an electric switch device, a base, a snap switch mechanism inclosed therein, an adjustable spindle carried by said base and means carried by said spindle for supporting a lamp socket.
8. In an electric switch device, the combination of a base, having a plurality of parts, a switch mechanism inclosed therein, terminal contacts for said switch mechanism arranged to hold parts of said base together, a threaded sleeve carried by said base and an adjustable socket supporting spindle carried by said sleeve, and means including a threaded spider for supporting said base.
9. In an electric switch device, in combination a base having a stepped surface arranged to support candles of different sizes, a snap switch mechanism inclosed in said base, an adjustable socket supporting spindle carried by said base and a threaded spider arranged to support said base.
10. In an electric switch device, a two part base, a snap switch mechanism inclosed therein, terminal contacts for said switch mechanism arranged to hold the parts of the base together, a threaded sleeve carried by said base, an adjustable socket supporting spindle carried in said sleeve and a pronged spider having a threaded sleeve, said spider being arranged to grip the base and be attached to a suitable support.
11. In an electric switch device, a receptacle, a base carried therein, a snap switch mechanism carried by said base including an operating member having detachable push buttons, said push buttons extending through openings in said receptacle, means for supporting a socket above said base, and means for attaching said base to a suitable support.
12. In an electric switch device, a two part base, a snap switch mechanism having removable push buttons inclosed therein, terminal contacts arranged to hold the parts of said base together, means for positioning said contacts in said base and means for attaching said base to a suitable support.
13. In an electric switch device, a two part base, terminal contacts extending therethrough and arranged to hold the parts of the base together, and a switch mechanism inclosed in said base and arranged to bridge said contacts, means for attaching said base to a suitable support and a socket supporting spindle carried by said base and insulated therefrom.
14. In an electric switch device, a base, a snap switch mechanism carried thereby, and means for supporting said base including a pronged spider having prongs of different lengths.
15. In an electric switch device, a base, a snap switch mechanism carried thereby, and means for supporting said base including a removable spider having prongs of different lengths, said prongs being arranged to grip said base in predetermined position.
16. In an electric fixture, a candle cup having holes in its periphery, a base carried in said cup, and a switch mechanism in said base, having removable push buttons extending through said holes in said candle cup.
17. In an electric fixture, a candle cup, a base carried in said cup, a switch mechanism inclosed in said base and operable from the exterior of said cup and a socket supporting spindle carried by said base.
18. In an electric fixture, a candle cup, a base carried in said cup, a snap switch mechanism inclosed in said base, a socket supporting spindle carried by said base and insulated thereby, and removable means for attaching said base to a suitable support.
19. In an electric fixture, a candle cup, a base mounted therein, a switch mechanism carried in said base and operable from the exterior of said cup, a socket supporting spindle carried by said base, a candle inclosing said spindle, and means carried by said spindle for positioning said candle.
20. In an electric fixture, a candle cup, a support therefor, a two-part base having a stepped upper surface carried in said cup, a snap switch mechanism inclosed in said base, a socket supporting spindle carried by said base and insulated therefrom, a candle carried upon the stepped surface of said base and inclosing said spindle, and means carried by said spindle for positioning said candle.
- In witness whereof, I have hereunto subscribed my name in the presence of two witnesses.
